(57) **CLAIM**

The ornamental design for a television screen protector, as shown and described.

DESCRIPTION

FIG. 1 is a front elevation view of a television screen protector showing our new design;

FIG. 2 is a rear elevation view thereof;

FIG. 3 is a right side view thereof; the left side being a mirror image of the shown.

FIG. 4 is a top plan view thereof;

FIG. 5 is a bottom plan view thereof; and,

FIG. 6 is an isometric view thereof.

The broken lines shown in FIG. 6 are for illustrative purposes only and form no part of the claimed design.
